UNITED STATES PATENT OFFICE

155,586

DESIGN FOR A LAMP HEAD

Harold W. Darr, Minneapolis, Minn., assignor to Clifford R. Myre, Paynesville, Minn.

Application June 9, 1949, Serial No. 3,148

Term of patent 14 years

(Cl. D48—20)

To all whom it may concern:

Be it known that I, Harold W. Darr, a citizen of the United States, residing at Minneapolis, in the county of Hennepin and State of Minnesota, have invented a new, original, and ornamental Design for Lamp Head, of which the following is a specification, reference being had to the accompanying drawing, forming part thereof.

Fig. 1 is a front perspective view of a lamp head, showing my new design,

Fig. 2 is a rear perspective view thereof, and

Fig. 3 is a rear perspective view of the end opposite to that shown in Fig. 2.

I claim:

The ornamental design for a lamp head, as shown.

HAROLD W. DARR.
